UNITED STATES PATENT OFFICE.

WILLIAM OWEN, OF PITTSBURGH, PENNSYLVANIA, ASSIGNOR TO PITTSBURGH PLATE GLASS COMPANY, A CORPORATION OF PENNSYLVANIA.

MACHINE FOR ROUNDING THE EDGES OF GLASS SHEETS.

Application filed April 8, 1926. Serial No. 100,652.

The invention relates to machines for rounding the edges of sheets, such as the glass sheets used in automobile wind shields and bodies. One of the most successful machines for doing this work comprises a series of wheels of abrading material placed in alignment, one after the other, and each having a plurality of circumferential grooves. A series of plates or sheets corresponding in number to the number of grooves in the wheels is carried over the wheels and round the edges of the plates on a curve corresponding to the curve of the grooves. One of the objections to this machine is the rapid wear of the wheels, which quickly alters the shape of the grooves so that the wheels must be resurfaced to bring the grooves back to their original contour.

This rapid wear is largely due to the unequal work imposed on the various portions of the surface of the grooves. Each sheet has two sharp corner edges, which must be cut away before the main part of the edge of the sheet is brought into contact with the surface of the groove. The surface of the groove is, therefore, rapidly worn away by the glass along the lines where the sharp corner edges of the sheets engage, so that the groove loses its shape, and becomes more and more unsuited to give the glass edges their proper shape. The present invention is designed to overcome this difficulty, by the addition of means which rough off the sharp corners edges of the sheet before such edges reach the rounded circumferential grooves heretofore referred to, so that such grooves are relieved of this work and caused to wear more uniformly, thus increasing the life of the grooves many times over. A further object of the invention is to provide a roughing grinder for the edges which is applicable as a unit to the multiple groove wheel type of edge machine, and to provide a roughing means which is self-dressing, so that such means requires attention only when completely worn out. One embodiment of the invention is illustrated in the accompanying drawings, wherein:

Figure 1 is a side elevation of a part of the machine. Fig. 2 is a partial plan view of the machine. Fig. 3 is a section on an enlarged scale on the line III—III of Fig. 1. And Fig. 4 is a section on the line IV—IV of Fig. 1.

Referring to the drawings, the framework of the machine is made up of a horizontal plate or table 1, a series of vertical angles 2, 2, 2, etc., and longitudinally extending bracing members 3. Carried upon this framework is a bridge comprising vertical members 4, 4, 4, etc., (Figs. 1 and 4) braced by diagonal members 5 and carrying longitudinally extending guides 6 and 7, the latter guide being hollow and carrying the upper flight of the drag chain 8. This drag chain passes around a pair of sprockets 9, 9 at the ends of the framework, only one of such sprockets being shown. This chain is driven in any suitable manner, and its lower flight is supported upon the top of the table 1, as indicated in Fig. 3.

The machine is designed to round the edges of six sheets of glass 10, 10, 10, etc., as indicated in Fig. 3, although this number may be varied to meet requirements. The sheets are placed upon the machine at the right hand end (Fig. 1) and dragged along over the abrading wheels by the lower flight of the chain 8, such chain being provided at intervals with the transverse members 11 (Fig. 3). These members have downwardly projecting lugs 12 secured to the chain 8 and also a pair of fingers 13, 13 fitting over a guide flange 14 on the table 1. The other ends of these members rest upon a guide 15 at the other side of the table, and intermediate the ends of the member are the fingers 16, 16, 16, etc., fitting between the sheets of glass and supporting them. These fingers project backwardly, as well as forwardly, as indicated in Fig. 1, so as to space and support the sheets of glass to the rear of the member as well as those in front of it. A second set of spacing and supporting members 17, 17, 17, etc., is carried by the guide member 8, such members being slidably supported upon such guide and having forwardly and rearwardly projecting fingers similar to those on the members 11. These members 17 serve to support the upper portions of the sheet, thus maintaining them in vertical position and at a proper distance apart and being moved along by the glass sheets themselves.

The roughing away of the edges of the sheets is accomplished by means of the plurality of pairs of cup grinding wheels 18, 19, 18, 19, etc., six pairs of these wheels

being employed to correspond to the six sheets of glass whose edges are to be rounded, the arrangement being such that each pair of wheels acts upon the two corner edges 5 of one of the sheets of glass. The sheets of glass are guided to the grinding wheels over the loading portion of the table at the right hand end of Fig. 1, such portion of the table being made up of the series of grooved rolls 20, 20, 20, etc., each of which is provided with a number of grooves corresponding with the number of sheets to be carried, as indicated in Fig. 2.

The sets of wheels 18, 19 are preferably 15 all driven from a single electric motor 21, as indicated in Fig. 2. The drive shaft of this motor is connected through a suitable coupling 22 with a pinion 23 in the casing 24, and this pinion drives all of the spur 20 gears 25, 25, 25, etc., mounted in the casing, the adjacent gears being driven in opposite directions. The ends of the shafts 26 which carry the gears are connected to flexible drive shafts 27, 27, 27, etc. The other ends 25 of such flexible drive shafts are connected to the spindles 28 of the grinding wheels, as indicated in Fig. 3. Each pair of grinding wheels is mounted in a casting 29, which includes a pair of sleeves 30, 30, in which the 30 bushings 31 and 32 are mounted, the spindles 28 being journaled in such bushings. The space 33 in each sleeve serves as an oil reservoir from which the bushings are lubricated, capillary oil feeding tubes 34 being 35 provided for oiling the thrust bearing at 35. The spindle is held in position in its bushings by the nuts 36, and the grinding wheels are secured to the spindle by means of the nuts 37. The castings 29 are each adjustable 40 vertically in a base casting 38 by means of the adjusting screws 39, the casting 29 having a shank 40 slidably mounted in the casting 38 and clamped in position by the bolt 41. The upper end of the casting 38 is split 45 in order to permit of this clamping function and in addition is provided with a slot 42 for guiding a pin 43 carried by the shank 40, so as to prevent such shank from rotating. In this manner, provision is made 50 for adjusting each pair of grinding wheels 18 and 19 vertically in order to take care of the wear which occurs at the grinding surfaces of the wheels. The edges of the grinding wheels are preferably located with 55 respect to the glass being cut so that the entire cutting surface of the grinding wheel is exposed to wear, which arrangement makes the wheels self-dressing so that they may be used until worn out without any requirement 60 for removal for the purpose of evening up the faces. The cutting faces of the wheels lie at approximately the angle indicated in Fig. 3, although this may be varied to meet requirements. A pan 44 with a splash guard 65 45 is preferably employed and the face of

the wheel may be moistened from a sponge 46 to which water is applied through the pipe 47.

The glass sheets are supported after they leave the grooved rollers 20, 20, 20 by blocks 48, 48, 48 (Fig. 3), preferably of rubber, such blocks being spaced between the wheels in order to support the sheets as they are carried along. These blocks are fastened to the table 1 by means of screws, as indicated in Fig. 3, and the table 1 is cut away so as to permit the passage of the edges of the grinding wheels therethrough, it being desirable to give the portions of the edges of the sheet which are not in contact with the grinding wheels as much support as possible in order to prevent any tilting action. The sharp corner edges of each glass sheet are ground away by the wheels 18 and 19, so that when these sets of wheels are passed, the edges require only a limited amount of grinding action in order to bring them to the desired curve and give them the desired amount of polish. In order to further support the edges of the sheet, the rubber covered rollers 49 (Fig. 3) are also provided between the grinding wheels, such rollers being carried upon spring arms 50 secured to the table.

The final grinding and polishing operation is given by means of a series of grinding wheels 51 at the left hand end of the machine (Fig. 1), only one of such wheels being shown, this type of wheel being well known in the art. As indicated in Fig. 4, the wheel is provided with six grinding grooves, corresponding to the number of plates which are to be treated, as heretofore set forth. The grooves 52 are in alignment with the edges of the glass sheets carried along by the drag chain, the sheets being supported intermediate the wheels upon grooved rubber blocks corresponding to the blocks 48 heretofore described in connection with Fig. 3. The grinding wheel is preferably supported upon the end of a driven shaft 53, provided with a drive pulley 54. The drive shaft and its motor (not shown) is preferably carried by a frame 55 pivotally supported at its left hand end (Fig. 1) and having its right hand end adjustable vertically by means of screws 56, this arrangement providing for the vertical adjustment of the wheel to properly position it and to take care of wear which occurs. The grinding wheel is preferably of the annular form shown and is supported upon a spider 57 bolted to the end of the shaft 53. A casting 58 surrounds the wheel and carries a lubricating fluid, such as water. The glass plates are carried by the drag chain over this wheel and a series of other similar wheels, thus giving the necessary finishing action and finally polishing the rounded edges.

In operation, the plates are mounted upon the rollers 20, 20, 20 in sets of six with the members 11 and 17 in engagement therewith, as indicated in Fig. 1, the fingers of such members lying between the plates and holding them in proper spaced relation. The driving of the chain 8 in the direction indicated by the arrows causes the members 11 to carry the series of plates over the sets of grinding wheels 18 and 19 and each sheet has its lower edge acted upon by one of the pairs of wheels, so that when the sheets have been carried past this grinding unit by the drag chain, their corner edges are beveled away, and only a slight amount of further grinding action is supplied by the series of wheels 51 whose grooved grinding surfaces give the sheets the desired contour, after which they pass over a suitable polishing wheel of similar contour. The work imposed upon the grinding wheels 51 by this operation is relatively slight, so that these wheels may be used for a long period of time without any requirement for redressing the grooves. The sets of grinding wheels 18 and 19 bear the brunt of the grinding action, but by reason of the fact that their grinding edges are self-dressing, the wheels have a relatively long life, the only attention which this unit requires being the vertical adjustment of the wheels from time to time, as heretofore described in order to compensate for the wear of the wheels.

What I claim is:

1. A machine for rounding the edges of glass sheets, comprising an abrading wheel provided with a plurality of circumferential grooves, a corresponding plurality of pairs

of roughing wheels arranged in series in staggered relation in advance of the grooved wheel, and means for supporting and carrying a plurality of sheets of glass in parallel relation over the roughing wheels and then over the grooved abrading wheel, the members of each pair of roughing wheels having their axes of rotation oppositely inclined obliquely to the plane of the sheets, so that the face of one of each pair of roughing wheels engages one of the corners at the edge of the sheet, and the other wheel of the pair engages the other corner at such edge of the sheet.

2. A machine for rounding the edges of glass sheets, comprising an abrading wheel provided with a plurality of circumferential grooves, a corresponding plurality of pairs of roughing wheels, arranged in series in staggered relation, in advance of the grooved wheel, and means for supporting and carrying a plurality of sheets of glass in parallel relation over the roughing wheels and then over the grooved abrading wheel, the members of each pair of roughing wheels having their axes of rotation on opposite sides of the line of travel of the sheet and arranged so that the cutting surface of one of each pair of roughing wheels engages one of the corners at the edge of the sheet, and the cutting surface of the other wheel of the pair engages the other corner at such edge of the sheet.

In testimony whereof, I have hereunto subscribed my name this 12th day of March, 1926.

WILLIAM OWEN.
